(57) **CLAIM**

The ornamental design for an adjustable, collapsible lounge chair with lumbar support, as shown.

DESCRIPTION

FIG. 1 is a front perspective view of an adjustable, collapsible lounge chair with lumbar support showing my new design;

FIG. 2 is a side elevation view showing the lounge chair in a second seating position, the opposite side being a mirror image thereof;

FIG. 3 is a view similar to FIG. 2 showing the lounge chair in a collapsed seating position, the opposite side being a mirror image thereof;

FIG. 4 is a top plan view thereof; and,

FIG. 5 is a rear elevation view thereof.

The portions of the article not shown in the drawing or described in the specification form no part of the claimed design.
